SPARK PLUG PUMP

Filed April 24, 1931

UNITED STATES PATENT OFFICE

DELPHIN H. SPICER, OF LAKEWOOD, OHIO, ASSIGNOR TO SPICER AIRFLATER, INC., OF CLEVELAND, OHIO, A CORPORATION OF OHIO

SPARK PLUG PUMP

Application filed April 24, 1931. Serial No. 532,538.

This invention relates to the art of pumping air or the like and has particular reference to an attachment for internal combustion motors and the combination of such attachments with such motors designed to be used for compressing air or other gases for such purposes as inflating pneumatic tires and the like.

I am aware that prior to my invention numerous devices have been proposed for use in connection with internal combustion motors for inflating tires and similar purposes but so far as I am aware none of these devices are capable of producing the results accomplished by the herein described invention.

The principal object of my invention is to provide an attachment of the character described by the use of which it is possible to inflate a tire or other receptacle to a very high pressure with substantially pure air. By pure air in this specification is understood air of substantially the composition of the atmosphere at the place where the device is used, that is, air which is substantially free from the fuel which is employed in the internal combustion engine in connection with which the device is used and also substantially free from the products of the combustion of such fuel.

I attain the foregoing and other and more limited objects in and through the structures hereinafter described and illustrated in the accompanying drawing in which Fig. 1 is a schematic sectional view taken longitudinally of my device; Fig. 2 is a section on the line 2-2 of Fig. 1; Fig. 3 is a section on the line 3-3 of Fig. 1; Fig. 4 is a section on the line 4-4 of Fig. 1; and Fig. 5 is a section on the line 5-5 of Fig. 1.

In the drawing I have shown schematically an internal combustion engine of usual construction such as employed in automobiles, trucks and similar vehicles. The numeral 10 indicates the wall of a cylinder provided with the usual water jacket space 11 defined between the wall 10 and the external wall 12. A cylinder head 13 of usual construction is indicated as being provided with a spark plug opening 14 in a depre-

sion 15 and provided with the usual water space 16. A gasket 17 seals the cylinder head 13 on the engine block indicated generally by the numeral B and is held firmly in place by suitable bolts (not shown). A piston C of usual construction works within the cylinder wall 10 and defines with the structures already described a combustion chamber D. It is to be understood that this motor is provided with the usual carburation device, inlet and exhaust valves with their operating means, crank shaft and connecting rod assembly and ignition means including a spark plug E which is normally received in the spark plug opening 14 but which may be positioned as indicated in Fig. 1 and will be so positioned when the device is in use.

The attachment comprises an elongated pumping cylinder F having a bore G 76 therein which acts as a pumping chamber, a spark plug socket H, a valve assembly K, a delivery nipple L and a delivery hose M.

The cylinder F is provided with an externally threaded lower end portion 18 of a size adapted to be received in the spark plug opening 14 and a shoulder 19 adapted to engage a gasket 20 for sealing the cylinder in communication with the combustion chamber D. It will be noted that the pumping chamber G is considerably elongated and that the communication thereof with the combustion chamber D is of a large size. It is preferably although not necessarily the same size as the remainder of the bore 80 G which preferably is substantially uniform in diameter.

The spark plug socket H is positioned near the lower end of the cylinder F and extends laterally outwardly therefrom. 90 This socket is so constructed that the spark plug E will not obstruct the bore G to any considerable extent. The spark plug socket H is internally threaded as indicated at 21 and provided with a flat surface 22 adapted 95 to cooperate with the shoulder 23 of the spark plug E whereby to effect with the gasket 24 a seal to prevent the escape of gas when the spark plug is in position.

The upper end of the cylinder F is pro- 100

vided with a shoulder 25 and an internally threaded terminal portion. Positioned within said cylinder and resting on the shoulder 25 is an annular stop or washer member 26. Above the washer 26 is a cup washer 27 which may be of such size as to be pressed into snug fitting relation with the walls of the cylinder. This washer is provided with a central aperture 28. Between 10 the washers 26 and 27 is a loosely mounted cut-off disk 29 provided with a small central aperture 30 and marginal cut-outs 31. Above the washer 27 is a valve disk 32 constructed of heat resistant rubber, fiber or 15 soft metal and provided with a central opening 33.

Threaded into the upper end of the cylinder F is a plug N which is provided with a series of openings 34 extending around the 20 edge thereof and having a central hollow projection 35 provided with a central valve chamber 36 and a reduced opening 37. A ball 38 is positioned in the valve chamber 36 and cooperates with the restricted opening 37 and the shoulder which connects it with the chamber 36 to form a check valve adapted to prevent the entrance of air through the opening 37 into the pumping chamber G. Threaded into the upper end 30 of the projection 35 is a delivery nipple 39 which is provided with a bore 40 and a kerfed lower face provided with one or more kerfs 41 intersecting the bore 40 to prevent the ball 38 from obstructing the passage of 35 air through the bore 40. Connected to the nipple 39 is the hose M which may have a flexible metallic portion 42 and a rubber or rubber and fiber portion 43.

The valve structure described is designed 40 to allow the ingress of air to the chamber G on the intake stroke with the greatest possible freedom while operating to cut off escape of air therefrom on the compression and firing strokes. In the use of this device 45 with the parts in the positions indicated and the spark plug connected with a high-potential electric supply, the operation will be as follows. On the intake stroke of the motor an explosive mixture will flow into 50 the combustion chamber D through the intake valve in the usual manner while fresh air will flow through the openings 34 into the pumping chamber G. The length and diameter of the chamber G is so selected 55 with reference to the resistance of the valve mechanism to the passage of air and the entire attachment will be so related to the resistance of the carburation device to the 60 passage of air and fuel into the combustion chamber D that under the various conditions of use little or no combustible mixture will find its way into the upper portion of the chamber G. On the compression stroke 65 of the motor the combustible mixture will

way into the upper portion thereof. It is desirable that on the compression stroke of the motor the combustible mixture should rise to a point at least as high as the 70 sparking points of the spark plug E. It is allowable that it should rise somewhat above these points but it should not find its way into the upper portion of the chamber. On the explosion stroke of the cylinder to which the device is attached a very considerable 75 pressure will be produced in the combustion chamber D and the gaseous products of combustion of the fuel will force the fresh air contained in the chamber G out through the outlet check valve into the hose M. It 80 is to be expected that there will be some mixture of the fresh air with the products of combustion in the chamber G but on account of the narrow and elongated nature 85 of this chamber the zone of mixing of such gases with the fresh air will be comparatively narrow and in embodiments of the invention correctly designed with reference to the conditions of use the zone of mixed air and products of combustion will remain 90 below the outlet check valve whereby only fresh air will be pumped through the hose M.

It is to be noted that by positioning the inlet valve mechanism adjacent the outlet valve mechanism at the upper end of the pumping cylinder, a mixture of the products of combustion with the fresh air is avoided. If the inlet valve were positioned lower down, fresh air might be admitted below the 95 region of contact between the products of combustion and fresh air thereby cutting off a portion of the products of combustion above the fresh air inlet and allowing the same to mix with the fresh air. By the use 100 of a substantially straight pumping chamber extending vertically from the spark plug opening in the motor, I secure not only a minimum of resistance to the passage of gases in the pumping chamber, but also 105 greater convenience in connecting the pumping unit with the motor.

For the best results, the various elements of the device should be so proportioned and of such dimensions that on the intake stroke, a sufficient amount of air will be drawn in to fill the pumping chamber substantially or completely full but not enough to cause any appreciable amount to enter the combustion chamber of the motor and thereby dilute the 110 combustible mixture.

Other means may be employed as a substitute for the portion of metallic hose to prevent damage to the rubber hose by heat. For example, some part of the mechanism 115 such as the plug N or the nipple L may be constructed of bakelite or similar heat insulated material.

From the foregoing, it will be obvious that I have provided a pump which is well adapt- 120

ed for its intended purpose and while I have shown and described the present preferred embodiment I do not wish to be limited to the details thereof except in accord 5 with the scope of the appended claims.

Having thus described my invention, what I claim is:

1. In combination with a cylinder of an internal combustion motor of usual construction including a piston, inlet and exhaust valves, timed means for operating said valves, and means for supplying fuel; an ignition means in communication with the combustion chamber of said motor, and an 10 explosion pump cylinder also in communication with said combustion chamber and having adjacent the end remote from said combustion chamber an outlet-check-valve means and being provided with an inlet-check- 15 valve means communicating between the interior thereof and outside atmosphere.

2. In combination with a functioning cylinder of an internal combustion motor, wall means defining an elongated pumping chamber, means connecting said pumping chamber in communication with the combustion chamber of said motor, means for connection of said chamber with a delivery device, an outlet-check-valve adjacent said last means, 20 and low resistance inlet-check-valve means communicating between said pumping chamber and outside atmosphere.

3. In combination with a functioning cylinder of an internal combustion motor, wall means defining an elongated pumping chamber, means connecting said pumping chamber in communication with the combustion chamber of said motor, means for connection of said chamber with a delivery hose, 25 an outlet-check-valve adjacent said last means, and low resistance inlet-check-valve means communicating between said pumping chamber and outside atmosphere.

4. An explosion pump unit adapted to be 30 connected with the combustion chamber of an internal combustion motor, including, wall means defining an elongated pumping chamber, a spark plug receiving socket formed in connection with said wall means and 35 communicating with said pumping chamber, means for connection of said chamber to a delivery hose, an outlet-check-valve adjacent said last means, and low resistance inlet- 40 check-valve means communicating between said pumping chamber and outside atmosphere, said inlet-check-valve comprising a plurality of openings formed in said wall means, a shoulder spaced from said openings, and a gasket loosely mounted between said 45 openings and said shoulder.

5. In combination with a functioning cylinder of an internal combustion motor, wall means defining an elongated pumping chamber, means connecting said pumping chamber in communication with the combustion 50

chamber of said motor, means for connection of said chamber with a delivery hose, an outlet-check-valve adjacent said last means, and low resistance inlet-check-valve means communicating between said pumping chamber 55 and outside atmosphere, said inlet-check-valve comprising a plurality of openings formed in said wall means, a shoulder spaced from said openings, and a gasket loosely mounted between said openings and 70 said shoulder.

6. In a device of the character described, a cylinder having one threaded end, a spark plug socket formed in connection with said cylinder and extending laterally therefrom, a plug in the opposite end of said cylinder, an annular, marginal series of openings extending through said plug, a central opening through said plug, a hose nipple communicating with said central opening, a ball valve controlling said central opening and acting as an outlet-check-valve, an annular shoulder spaced from the bottom of said plug, and an annular gasket between said 75 openings in said plug and said shoulder. 80

7. The method of introducing fresh air under pressure into a receiver which consists in establishing communication through an elongated passage between said receiver and the combustion chamber of a cylinder of an internal combustion motor during the firing 85 strokes of such cylinder and cutting off said communication and clearing said passage of cylinder gases and replacing such gases with fresh air between firing strokes. 90

In testimony whereof, I hereunto affix my signature.
